UNITED STATES PATENT OFFICE.

CHARLES W. HENSON, OF CHICAGO, ILLINOIS.

GAS-REGULATOR.

SPECIFICATION forming part of Letters Patent No. 794,980, dated July 18, 1905.

Application filed March 13, 1905. Serial No. 249,725.

To all whom it may concern:

Be it known that I, CHARLES W. HENSON, a citizen of the United States, residing in Chicago, in the county of Cook and State of Illinois, have invented a new and useful Improvement in Gas-Regulators, of which the following is a specification.

This invention relates to the construction of regulators for regulating the pressure of gas in dwellings and buildings. Its object is to prevent excessive pressure at the burners, thereby avoiding all wasteful consumption of the gas.

The invention consists in the novel construction of parts and devices and the novel combinations of parts and devices hereinafter described.

In the accompanying drawings, forming a part of this specification, Figure 1 is a central vertical section of the invention, and Fig. 2 is a horizontal section on the line 2 2 of Fig. 1.

In the drawings, 3, 4, and 5 represent sections forming the vertical walls of a suitable casing having a top 6 and a bottom 7. The upper section is united to the top by a flanged ring 8, and the bottom is united to the lower section by a similar ring 9. The sections 3 and 4 are united by a flanged ring 10, fitted over a flange 11 of section 3 and threaded 30 upon the flange 12 of section 4, and sections 4 and 5 are similarly secured together by flanged ring 13, fitting over flange 14 on section 4 and threaded on flange 15 of section 5.

The interior of the casing is divided horizontally into three chambers 16, 17, and 18 by means of two partitions or divisions 19 and 20, one supported at its edges in the joint between sections 3 and 4 and the other in a similar manner in the joint between sections 4 and 5. In partition 19 is an annular depression or groove 21, adapted to hold a fluid wherewith to establish a seal between chambers 16 and 17, and in partition 20 is a similar annular groove 22, of less diameter, however, than the groove 21, but adapted to hold a fluid body and establish a seal between chambers 17 and 18. Air may be and preferably is admitted freely to the chamber 17

by means of the openings 23. The gas enters the regulator at 24 and issues therefrom at 25.

Extending vertically through the center of the partitions with freedom to move vertically is a tube 26, forming a passage for the gas from chamber 18 to chamber 16. Surrounding the tube are cylindrical guide portions 29 and 32 of the partitions, which, however, fit the tube loosely, so as not to exert friction thereon. To the top of the tube is secured a bell 27, through the pressure upon the top of which the tube is depressed when the consumption of gas is reduced. The depending edge of this bell enters the groove 21 of the upper partition below the top of the mercury 28 therein, thus establishing a seal which prevents gas from chamber 16 gaining access to the inside of the bell, which would result in a contrary or upward pressure. This seal also prevents the escape of the gas through the space between the tube and the guide 29 into chamber 17. Said tube also carries a second bell 30, the lower edge of which dips into mercury 31 in the groove 22 of the lower partition, and thus establishes a seal which prevents the gas in chamber 18 from escaping in any way other than through the tube, except that some of it may find its way into the interior of this bell 30 by reason of the looseness of the fit between the tube and guide 32. The gas so entering the bell creates some upward pressure of course; but that is rendered immaterial by the small diameter of the bell as compared with the large diameter of the bell 27, by which the tube is depressed. The seals effected by the two bodies of mercury 28 and 31 are never broken while the regulator is in use, the vertical movements of the tube never being sufficient to carry the bells entirely above the mercury, so that no loss of gas occurs at the central chamber. As the tube is necessarily sensitive to the pressure upon the bell 27, it will be seen that there must be as little friction with the bearings or guides 29 and 32 as possible.

The gas from chamber 18 enters the tube

at the bottom of the latter and in the volume
desired for consumption in the house or building
and issues from thence into chamber 16,
and in order to regulate the capacity of the
5 opening into the tube I provide a ball 33, floating
in a body of mercury 34 in a well 35,
formed in the bottom 7 directly below the
tube. This ball is adapted, in conjunction
with the rising and falling tube, to shut off
10 the gas wholly from the tube or to admit it
thereto in just the volume required for con-
sumption, these results being obtained by the
vertical movements of the tube, due in one
15 direction to the pressure of the gas in cham-
ber 16 on top of the large bell 27, aided by
gravity, and in the other direction to the
power of a lifting-spring 36, aided by the up-
ward pressure inside the bell 32. The spring
20 36 is secured at one end to a transverse pin
37 in the lower end of the tube and at its
other end to a winged nut 38 on the revoluble
threaded rod 39, passing downward through
the top 6 of the casing and provided with an
operating - knob 40. The wings of the nut
25 move in vertical slots cut in the sides of a
guide-tube 41, encircling the rod, so that the
nut cannot revolve with the rod, but is free
to move up and down on the rod when the lat-
ter is turned. In these movements the nut
30 either increases or decreases the tension upon
the spring 36, as will be understood, so the
spring will yield more readily or less readily
to the pressure on bell 27. The rod is pro-
vided with a collar 42, seated on a shoulder
35 in the top 6, and a packing-nut 43, threaded
into the opening in the top through which the
rod passes, and a packing 44 to prevent gas
from escaping from the top chamber and
serve to hold the rod down, with the collar
40 resting on its seat.

The ball 33 is preferably made with its bottom half larger than its top half, thereby increasing its weight above what it would be if made of the smaller diameter throughout.

45 The upper portion is adapted to effect a tight joint with the tube; but the increased weight prevents it from being lifted up into the tube when the pressure is suddenly lessened or withdrawn in chamber 16, as may sometimes happen. By supporting the ball in a fluid it is enabled to yield should the tube descend suddenly, and it finds its correct seat easily and quickly and without jar.

55 I have mentioned mercury as a desirable medium for effecting the seals between the chambers and as the fluid supporting the ball 33; but it will be understood that I do not wish to be limited thereto, as the only change in construction of the apparatus necessitated
60 by the use of a sealing liquid of less specific gravity would be an increase in the vertical dimensions of the liquid-holding parts and of the bells dipping into the liquid. I have in-

dicated a different level of the sealing fluid on the inside of each bell from that on the outside. This I do on the theory that the fluid on the side where the superior pressure exists will be forced to a lower level than will the fluid on the side where the pressure was less. 65

In order that there may be no loss of the mercury while the regulator is stored or being transported to the place of use and be ready for use as soon as it is connected to the gas-main and the supply-pipe of the house, I place interior thimbles 46 in the openings 23 and also extend the pipes 24 and 25 into the casing for quite a distance, as shown, so that if the regulator were laid on its side or even reversed none of the mercury would escape from the chamber in which it belongs. I also preferably dish the tops of the partitions 19 and 20 and bottom 7 to the centers, so that when the regulator is positioned upright after being tipped far enough to allow the mercury to run out of its proper receptacles the mercury will at once return to operative position in the receptacles. 75 80 85

It may be desirable to cover the mercury both from the air and from the gas. For this purpose I place over it a quantity of some non-volatile liquid having less specific gravity than the liquid, preferably glycerin. Such a protecting liquid is indicated at 50 in the drawings. 95

The operation of the invention is as follows: After the regulator has been properly connected I admit the gas to it and raise the tube 26 by turning rod 40 sufficiently to permit an excess volume to move into the chamber 16 100 and then light a burner. I then turn the rod, so as to carry the nut 38 down and lessen the tension on the spring, thereby permitting the pressure on bell 27 to carry the tube 26 down toward the ball 33 and diminish the entrance-opening to the tube. When the flame at the burner ceases to blow, it indicates that the right pressure exists in chamber 16 and that the regulator is in proper condition to maintain a steady pressure in said chamber, notwithstanding variations in the amount of gas burned. This it does by reason of the tube being automatically lifted by the spring whenever the increase in the consumption reduces the pressure on bell 27 sufficiently to permit 115 the spring to act and increase the capacity of the inlet at its bottom, the tube being also automatically depressed by the pressure on bell 27 whenever the amount burned is so reduced as to cause an increase in that pressure 120 sufficient to overcome the spring, thereby reducing the capacity of the inlet, so that the excess pressure in chamber 16 quickly disappears.

I claim—

1. The gas-regulator embodying a movable

5 tube through which the gas passes and the entrance to which is controlled by positioning the tube vertically, a bell on the tube exposed to the gas at the discharge end of the tube and acting to depress it so as to reduce the supply when the amount of gas burned is reduced; and a lifting-spring acting to raise the tube and increase the supply when the amount burned increases so as to reduce the pressure 10 on the bell.

15 2. The gas-regulator embodying a movable tube through which the gas moves, and the entrance to which is controlled by positioning the tube vertically, of a bell on the tube exposed to the gas at the discharge end of the tube and depressing the same when the pressure thereon exceeds the desired normal pressure, and a spring lifting the tube when the 20 said pressure falls below normal.

25 3. The gas-regulator embodying a movable tube through which the gas moves, and the entrance to which is controlled by positioning the tube vertically, of a surrounding device mounted on the tube and receiving the pressure of the gas at the discharge end of the tube, and depressing the same when the pressure thereon exceeds the desired normal pressure, and a spring lifting the tube when said 30 pressure falls below normal.

35 4. The gas-regulator having a receiving-chamber, a discharge-chamber, and a movable tube through which the gas passes from one to the other, said tube also acting by its own positioning to regulate the supply passing through it, of means on said tube whereby it may be automatically depressed when the pressure in the discharge-chamber rises above the 40 desired normal pressure.

45 5. The gas-regulator having a receiving-chamber, a discharge-chamber, and a movable tube through which the gas passes from one to the other, said tube also acting by its own positioning to regulate the supply passing through it, of means on said tube whereby it may be automatically depressed when the pressure in the discharge-chamber rises above the 50 desired normal pressure, and means for lifting the tube when the pressure in the discharge-chamber falls below normal.

55 6. The gas-regulator having a receiving-chamber, a discharge-chamber, and a movable tube through which the gas passes from one to the other, said tube also acting by its own positioning to regulate the supply passing through it, of a bell mounted on the tube in the discharge-chamber and acting to depress the tube when the pressure in the chamber rises above the desired normal pressure.

60 7. The gas-regulator having a receiving-chamber, a discharge-chamber, and a movable open-ended tube through which the gas passes from one to the other, said tube also acting by its own positioning to regulate the

supply passing through it, of a bell mounted on the tube in the discharge-chamber and 65 acting to depress the tube when the pressure in the chamber rises above the desired normal pressure, and means for effecting a liquid seal at the bottom of said bell.

70 8. The gas-regulator having a receiving-chamber, a discharge-chamber, and a movable tube through which the gas passes, from one to the other, said tube also acting by its own positioning to regulate the supply passing through it, of a bell mounted on the tube in 75 the discharge-chamber and acting to depress the tube when the pressure in the chamber rises above the desired normal pressure, and a spring for lifting the tube when the pressure in the chamber falls below the desired 80 normal pressure.

85 9. The gas-regulator having a receiving-chamber, a discharge-chamber, and a movable tube through which the gas passes from one to the other, said tube also acting by its own positioning to regulate the supply passing through it, of means on said tube whereby it may be automatically depressed when the pressure in the discharge-chamber rises above the desired normal pressure, and a spring for 90 lifting the tube when the pressure in said discharge-chamber falls below the normal pressure, said spring also acting as a means whereby to adjust the regulator at the desired 95 normal pressure.

100 10. The gas-regulator having a receiving-chamber, a discharge-chamber, and a movable tube through which the gas passes from one to the other, said tube also acting by its own positioning to regulate the supply passing through it, of means on said tube whereby it may be automatically depressed when the pressure in the discharge-chamber rises above the desired normal pressure, a spring for lifting the tube when the pressure in said discharge-chamber falls below the normal pressure, and means for adjusting the tension of 105 said spring.

110 11. The gas-regulator having a receiving-chamber, a discharge-chamber, an open-ended tube connecting said chambers and movable in accordance with the pressure in the discharge-chamber, and also acting by its own positioning as a regulator of the supply to that chamber, and means for moving the tube 115 in accordance with the pressure in the discharge-chamber.

120 12. The gas-regulator having a receiving-chamber, a discharge-chamber, a tube connecting said chambers and movable in accordance with the pressure in the discharge-chamber, and also acting by its own positioning as a regulator of the supply to that chamber, a bell of large diameter on the tube having a liquid seal at its bottom and serving to depress the tube when the pressure in the dis- 125

charge-chamber rises above the desired normal pressure, and a second bell of small diameter also mounted on the bell and having a liquid seal and serving to prevent the escape 5 of gas from the receiving-chamber.

13. The combination with the vertically-movable regulating-tube, of the floating ball 33 acting with the tube to regulate the volume of gas passing through the tube and means 10 for positioning the tube vertically with reference to the ball.

14. The gas-regulator having the openings in its sides guarded by thimbles or pipes extending into the interior as specified, to avoid

loss of the liquid-sealing fluid during ship- 15
ment of the regulator.

15. The gas-regulator having the openings in its sides guarded by thimbles or pipes extending into the interior as specified, to avoid loss of the liquid-sealing fluid during ship- 20
ment of the regulator and also having a partition or bottom the top of which is dished so that the sealing fluid will automatically run to its operating position.

CHARLES W. HENSON.
